Emily Wilkens, New York, N. Y.

Application February 24, 1944, Serial No. 112,696

Term of patent 3½ years

(CL. D3—26)

To all whom it may concern:

Be it known that I, Emily Wilkens, a citizen of the United States of America, residing in the city of New York, county of New York, and State of New York, have invented a new, original, and ornamental Design for a Pinafore, of which the following is a specification, reference being had to the accompanying drawing, forming part thereof,

Fig. 1 is a front view of a pinafore showing my new design.

Fig. 2 is a rear view thereof.

I claim:

The ornamental design for a pinafore, substantially as shown.

EMILY WILKENS,
